(57) **CLAIM**

The ornamental design for a corner protector, as shown and described.

DESCRIPTION

FIG. 1 is a top front perspective view of a corner protector according to the present design;

FIG. 2 is a top rear perspective view of the corner protector according to the design shown in FIG. 1;

FIG. 3 is a bottom rear perspective view of the corner protector according to the design shown in FIG. 1;

FIG. 4 is a front side view of the corner protector according to the design shown in FIG. 1;

FIG. 5 is a rear side view of the corner protector according to the design shown in FIG. 1;

FIG. 6 is a right side view of the corner protector according to the design shown in FIG. 1;

FIG. 7 is a left side view of the corner protector according to the design shown in FIG. 1;

FIG. 8 is a top view of the corner protector according to the design shown in FIG. 1;

FIG. 9 is a bottom view of the corner protector according to the design shown in FIG. 1;

FIG. 10 is a top front perspective view of an alternate embodiment of a corner protector;

FIG. 11 is a top rear perspective view of the alternate embodiment of the corner protector according to the design shown in FIG. 10;

FIG. 12 is a bottom rear perspective view of the alternate embodiment of the corner protector according to the design shown in FIG. 10;

FIG. 13 is a front side view of the alternate embodiment of the corner protector according to the design shown in FIG. 10;

FIG. 14 is a rear side view of the alternate embodiment of the corner protector according to the design shown in FIG. 10;

FIG. 15 is a right side view of the alternate embodiment of the corner protector according to the design shown in FIG. 10;

FIG. 16 is a left side view of the alternate embodiment of the corner protector according to the design shown in FIG. 10;

FIG. 17 is a top view of the alternate embodiment of the corner protector according to the design shown in FIG. 10; and,

FIG. 18 is a bottom view of the alternate embodiment of the corner protector according to the design shown in FIG. 10.
